CLAIM

An ornamental design for a decorative tooth pick, as shown and described.

DESCRIPTION

FIG. 1 is a perspective view of the decorative tooth pick in the environment of a martini glass.

FIG. 2 is a perspective front view of the decorative tooth pick.

FIG. 3 is a top view of the decorative tooth pick.

FIG. 4 is a bottom view of the decorative tooth pick.

FIG. 5 is a front view of the decorative tooth pick.

FIG. 6 is a rear view of the decorative tooth pick.

FIG. 7 is a right side view of the decorative tooth pick; and, FIG. 8 is a left side view of the decorative tooth pick.

The long dashed lines in FIG. 1 represent unclaimed subject matter comprising a martini glass, and two olives.
